CLAIM

The ornamental design for a combined ceiling fan and light kit, as shown and described.

DESCRIPTION

FIG. 1 is a side, bottom perspective view of a combined ceiling fan and light kit showing my new design without the light kit attached;

FIG. 2 is a top plan view thereof;

FIG. 3 is a bottom view thereof;

FIG. 4 is a side elevational view thereof, the remaining side views being substantially the same;

FIG. 5 is a side, bottom perspective view of a combined ceiling fan and light kit showing a first embodiment of my new design;

FIG. 6 is a top plan view of the combined ceiling fan and light kit shown in FIG. 5;

FIG. 7 is a bottom plan view of the combined ceiling fan and light kit shown in FIG. 5;

FIG. 8 is a side elevational view of the combined ceiling fan and light kit shown in FIG. 5 the remaining side views being substantially the same;

FIG. 9 is a side, bottom perspective view of a combined ceiling fan and light kit showing a second embodiment of my new design;

FIG. 10 is a top plan view of the combined ceiling fan and light kit shown in FIG. 9;

FIG. 11 is a bottom plan view of the combined ceiling fan and light kit shown in FIG. 9; and,

FIG. 12 is a side elevational view of the combined ceiling fan and light kit shown in FIG. 9, the remaining side views being substantially the same.
